[57] CLAIM

The ornamental design for a ribbon dispenser, as shown and described.

DESCRIPTION

FIG. 1 is a top, left front perspective view of a ribbon dispenser showing my new design;

FIG. 2 is a top plan view on an enlarged scale;

FIG. 3 is a bottom plan view of FIG. 2;

FIG. 4 is a right side elevational view of FIG. 2, the left side being a mirror image thereof;

FIG. 5 is a front elevational view of FIG. 2; and

FIG. 6 is a rear elevational view of FIG. 2.

FIG. 1

FIG. 2

FIG. 3

FIG. 4

FIG. 5

FIG. 6
